(57) **ABSTRACT**

A dishwasher appliance includes a tub defining a wash chamber and a wash conduit in the wash chamber. A third rack assembly is slidably positioned in the wash chamber above the second rack assembly with a third spray assembly positioned within the third rack assembly. The third spray assembly is configured to direct wash fluid at articles located in the third rack assembly. The third spray assembly includes a protrusion positioned at a bottom portion of the third spray assembly. The protrusion is attachable to the third rack assembly in order to mount the third spray assembly to the third rack assembly.

FIG. 1

FIG. 2

FIG. 3

FIG. 4

FIG. 5

FIG. 6

SYSTEMS FOR MOUNTING SPRAY ASSEMBLIES IN DISHWASHER APPLIANCES

FIELD OF THE INVENTION

The present subject matter relates generally to systems for mounting a spray assembly in a dishwasher appliance, particularly relating to third racks in dishwasher appliances.

BACKGROUND OF THE INVENTION

Dishwasher appliances generally include rack assemblies for positioning various articles for cleaning within a wash chamber. One or more devices, such as nozzles or spray assemblies, may be included at various locations relative to the rack assemblies for purposes of delivering fluids as part of the cleaning process. During the cleaning cycle, the rack assemblies can support and position the articles while also having openings that allow fluid to pass through to the articles. Factors, such as the velocity of the fluid, orientation of the fluid spray or stream relative to the articles, the shape and density of the articles in the rack assemblies, and others, can impact the effectiveness of the cleaning cycle.

One or more rack assemblies may be used in dishwasher appliances for user convenience. Multiple rack assemblies on multiple levels within dishwasher appliances may allow users to place articles of differing heights and sizes in optimal positions to allow for proper cleaning of the articles. Some dishwasher appliances may include one or more baskets which may also be provided for holding articles, particularly smaller or for more narrow articles, such as silverware. Additionally, the user may have the option of, e.g., placing articles, such as silverware, within a basket on a lower rack assembly or placing the silverware directly (without the basket) onto an upper rack assembly specially configured for the receipt of such articles.

The positioning of articles within a dishwasher appliance can affect the fluid dynamics to which the articles are exposed during the cleaning process. For example, articles placed in a lower rack assembly may be subjected to different spray assemblies with different spray patterns, velocities, and spray duration than articles placed in a higher rack assembly. As dishwasher appliances have begun including more racks, space and positioning of dishwashing components inside of the dishwasher is important to ensure proper washing.

BRIEF DESCRIPTION OF THE INVENTION

Aspects and advantages of the invention will be set forth in part in the following description, or may be apparent from the description, or may be learned through practice of the invention.

In one example embodiment, a dishwasher appliance defines a vertical direction, a lateral direction, and a transverse direction. The vertical, lateral, and transverse directions are mutually perpendicular. The dishwasher appliance includes a tub defining a wash chamber and a wash conduit in the wash chamber. The dishwasher appliance also includes a first rack assembly slidably positioned within the wash chamber and a first spray assembly positioned in the wash chamber. The first spray assembly is configured to direct wash fluids at the first rack assembly. A second rack assembly is slidably positioned in the wash chamber above the first rack assembly with a second spray assembly positioned in the wash chamber and configured to direct wash

fluids at the second rack assembly. A third rack assembly is slidably positioned in the wash chamber above the second rack assembly with a third spray assembly positioned within the third rack assembly. The third spray assembly is configured to direct wash fluid at articles located in the third rack assembly. The third spray assembly includes a protrusion positioned at a bottom portion of the third spray assembly. The protrusion is attachable to the third rack assembly in order to mount the third spray assembly to the third rack assembly.

In another example embodiment, a dishwasher appliance defines a vertical direction, a lateral direction, and a transverse direction. The vertical, lateral, and transverse directions are mutually perpendicular. The dishwasher appliance includes a tub defining a wash chamber and a wash conduit in the wash chamber. The dishwasher appliance also includes a first rack assembly slidably positioned within the wash chamber and a first spray assembly positioned in the wash chamber. The first spray assembly is configured to direct wash fluids at the first rack assembly. A second rack assembly is slidably positioned in the wash chamber above the first rack assembly with a second spray assembly positioned in the wash chamber and configured to direct wash fluids at the second rack assembly. A third rack assembly is slidably positioned in the wash chamber above the second rack assembly with a third spray assembly positioned within the third rack assembly. The third spray assembly is configured to direct wash fluid at articles located in the third rack assembly. The third spray assembly includes a protrusion positioned at a bottom portion of the third spray assembly. The protrusion is attachable to the third rack assembly in order to mount the third spray assembly to the third rack assembly. The third spray assembly also includes a channel portion that is configured to engage third rack assembly in order to guide one end of the third spray assembly into a mounting position.

These and other features, aspects and advantages of the present invention will become better understood with reference to the following description and appended claims. The accompanying drawings, which are incorporated in and constitute a part of this specification, illustrate embodiments of the invention and, together with the description, serve to explain the principles of the invention.

BRIEF DESCRIPTION OF THE DRAWINGS

A full and enabling disclosure of the present invention, including the best mode thereof, directed to one of ordinary skill in the art, is set forth in the specification, which makes reference to the appended figures.

FIG. 1 provides a perspective view of an example embodiment of a dishwashing appliance of the present disclosure.

FIG. 2 provides a side, cross sectional view of the example dishwashing appliance of FIG. 1.

FIG. 3 provides a perspective view of an example embodiment of a rack of the dishwashing appliance of FIG. 1.

FIG. 4 provides a perspective view of an example embodiment of the rack of FIG. 3 with a wire insert in an open position.

FIG. 5 provides a bottom view of an example embodiment of a third spray assembly according to aspects of the present disclosure.

FIG. 6 provides a top perspective view of an example embodiment of a third spray assembly according to aspects of the present disclosure.

FIG. 7 provides a perspective view of the third spray assembly of FIG. 6 in a mounting position according to aspects of the present disclosure.

FIG. 8 provides a bottom perspective of an example embodiment of the rack of FIG. 3, with a support wire beneath the third spray assembly.

Repeat use of reference characters in the present specification and drawings is intended to represent the same or analogous features or elements of the present invention.

DETAILED DESCRIPTION OF THE INVENTION

Reference now will be made in detail to embodiments of the invention, one or more examples of which are illustrated in the drawings. Each example is provided by way of explanation of the invention, not limitation of the invention. In fact, it will be apparent to those skilled in the art that various modifications and variations can be made in the present invention without departing from the scope or spirit of the invention. For instance, features illustrated or described as part of one embodiment can be used with another embodiment to yield a still further embodiment. Thus, it is intended that the present invention covers such modifications and variations as come within the scope of the appended claims and their equivalents.

As used herein, the terms "includes" and "including" are intended to be inclusive in a manner similar to the term "comprising." Similarly, the term "or" is generally intended to be inclusive (i.e., "A or B" is intended to mean "A or B or both"). Approximating language, as used herein throughout the specification and claims, is applied to modify any quantitative representation that could permissibly vary without resulting in a change in the basic function to which it is related. Accordingly, a value modified by a term or terms, such as "about," "approximately," and "substantially," are not to be limited to the precise value specified. In at least some instances, the approximating language may correspond to the precision of an instrument for measuring the value. For example, the approximating language may refer to being within a 10 percent margin.

As used herein, the term "article" may refer to, but need not be limited to dishes, pots, pans, silverware, and other cooking utensils and items that can be cleaned in a dishwashing appliance. The term "wash cycle" is intended to refer to one or more periods of time during which a dishwashing appliance operates while containing the articles to be washed and uses a detergent and water, preferably with agitation, to e.g., remove soil particles including food and other undesirable elements from the articles. The term "rinse cycle" is intended to refer to one or more periods of time during which the dishwashing appliance operates to remove residual soil, detergents, and other undesirable elements that were retained by the articles after completion of the wash cycle. The term "drain cycle" is intended to refer to one or more periods of time during which the dishwashing appliance operates to discharge soiled water from the dishwashing appliance. The term "cleaning cycle" is intended to refer to one or more periods of time that may include a wash cycle, rinse cycle, and/or a drain cycle. The term "wash fluid" refers to a liquid used for washing and/or rinsing the articles and is typically made up of water that may include other additives such as detergent or other treatments.

FIGS. 1 and 2 depict an example domestic dishwasher or dishwashing appliance 100 that may be configured in accordance with aspects of the present disclosure. For the particular embodiment of FIGS. 1 and 2, the dishwasher

appliance 100 includes a cabinet 102 (FIG. 2) having a tub 104 therein that defines a wash chamber 106 for receipt of articles 94 for washing. As shown in FIG. 2, tub 104 extends between a top 107 and a bottom 108 along a vertical direction V, between a pair of opposing side walls 110 along a lateral direction L, and between a front side 111 and a rear side 112 along a transverse direction T. Each of the vertical direction V, lateral direction L, and transverse direction T are mutually perpendicular to one another.

10 In this regard, as used herein, the terms "cabinet," "housing," and the like are generally intended to refer to an outer frame or support structure for appliance 100, e.g., including any suitable number, type, and configuration of support structures formed from any suitable materials, such as a system of elongated support members, a plurality of interconnected panels, or some combination thereof. It should be appreciated that cabinet 102 does not necessarily require an enclosure and may simply include open structure supporting various elements of appliance 100. By contrast, cabinet 102 15 may enclose some or all portions of an interior of cabinet 102. It should be appreciated that cabinet 102 may have any suitable size, shape, and configuration while remaining within the scope of the present subject matter.

The tub 104 includes a front opening 114 and a door 116 20 hinged at its bottom 117 for movement between a normally closed vertical position (shown in FIG. 1), wherein the wash chamber 106 is sealed shut for washing operation, and a horizontal open position for loading and unloading of articles from the dishwasher appliance 100. According to 25 example embodiments, dishwasher appliance 100 further includes a door closure mechanism or assembly 118 that is used to lock and unlock door 116 for accessing and sealing wash chamber 106.

At least one rack assembly is slidably positioned within 30 wash chamber 106 and is configured for the receipt of articles for cleaning. For the example embodiment shown in FIG. 2, opposing tub sidewalls 110 accommodate a plurality of rack assemblies. More specifically, guide rails 96, 98 and 35 120 may be mounted to (or formed as part of) sidewalls 110 for supporting a first rack assembly 122 (also referred to as a lower rack assembly 122), a middle rack assembly 124 (also referred to as a second rack assembly 124), and a third rack assembly 126 (also referred to as an upper rack assembly 126). As illustrated, upper rack assembly 126 is positioned 40 at a top portion of wash chamber 106 above middle rack assembly 124, which is positioned above lower rack assembly 122 along the vertical direction V. Additional details regarding the upper rack assembly 126 will be provided herein. For this example embodiment, upper rack assembly 126 is supported on opposing sidewalls 110 by 45 rails 120 but rails 120 could be supported on and attached to middle rack assembly 124 as well.

Each rack assembly 122, 124, 126 is adapted for movement along transverse direction T between an extended 50 loading position (not shown) in which the rack is substantially positioned outside the wash chamber 106, and a retracted position (shown in FIGS. 1 and 2) in which the rack is located inside the wash chamber 106. This may be facilitated, for example, by rollers, or guide wheels 128 55 mounted onto rack assemblies 122, 124, 126, respectively. Although guide rails 96, 98, 120 and guide wheels 128 are illustrated herein as facilitating movement of the respective rack assemblies 122, 124, 126, it should be appreciated that any suitable sliding mechanism or member may be used 60 according to alternative embodiments. In some embodiments, dishwasher appliance 100 may accommodate a different number of rack assemblies and supporting guide rails.

For example, dishwasher appliance 100 may accommodate only first rack assembly 122 and upper rack assembly 126, with accompanying guide rails.

Some or all of the rack assemblies 122, 124, 126 may be fabricated into lattice, or grid pattern, structures including a plurality of wires or elongated members 130 (for clarity of illustration, not all elongated members making up rack assemblies 122, 124, 126 are shown in FIG. 2). The plurality of wires or elongated members 130 may be either steel and stainless steel, and the wire may be coated with none, one, or more of nylon and polyvinyl chloride. Rack assemblies 122, 124, 126 are generally configured for supporting articles 94 within wash chamber 106 while allowing a flow of wash fluid to reach and impinge on those articles, e.g., during a cleaning or rinsing cycle. For some embodiments, a silverware basket (not shown) is removably attached to a rack assembly, e.g., lower rack assembly 122, for placement of silverware, utensils, and the like, that are otherwise too small or delicate to be accommodated by rack 122.

At least one spray assembly is located in wash chamber 106 and is configured to direct wash fluids onto at least one rack assembly for washing articles located therein. For the example embodiment of FIG. 2, dishwasher appliance 100 further includes a plurality of spray assemblies for urging a flow of water or wash fluid onto the articles placed within wash chamber 106. More specifically, as illustrated in FIG. 2, dishwasher appliance 100 includes a lower spray assembly 134 (also referred to as a lower spray arm assembly 134) disposed in a lower region 136 of wash chamber 106 and above a sump 138 so as to rotate in relatively close proximity to lower rack assembly 122. Similarly, a mid-level spray assembly 140 is located in an upper region 137 of wash chamber 106 and may be located below and in close proximity to middle rack assembly 124. In this regard, mid-level spray arm assembly 140 may generally be configured for urging a flow of wash fluid up through middle rack assembly 124 and third rack assembly 126. Additionally, an upper spray assembly 142 may be located above upper or third rack assembly 126 along the vertical direction V. In this manner, upper spray assembly 142 may be configured for urging and/or cascading a flow of wash fluid downward over rack assemblies 122, 124, and 126.

The various spray assemblies and manifolds described herein may be part of a fluid distribution system or fluid circulation assembly 150 for circulating water and wash fluid in the tub 104. More specifically, fluid circulation assembly 150 includes a pump 152 for circulating water and wash fluid (e.g., detergent, water, and/or rinse aid) in the tub 104. Pump 152 may be located within sump 138 or within a machinery compartment located below sump 138 of tub 104, as generally recognized in the art. Fluid circulation assembly 150 may include one or more fluid conduits or circulation piping for directing water and/or wash fluid from pump 152 to the various spray assemblies and manifolds. For example, as illustrated in FIG. 2, a primary supply conduit 154 may extend from pump 152, along rear side 112 of tub 104 along the vertical direction V to supply wash fluid throughout wash chamber 106. In some examples, a secondary supply conduit (not shown) may supply additional wash fluid to one or more various spray assemblies and manifolds.

As illustrated, primary supply conduit 154 is used to supply wash fluid to mid-level spray arm assembly 140 while a secondary supply conduit 92 supplies wash fluid to upper spray assembly 142. Diverter assembly 156 can allow selection between spray assemblies 134 and 140, 142 being supplied with wash fluid. However, it should be appreciated

that according to alternative embodiments, any other suitable plumbing configuration may be used to supply wash fluid throughout the various spray manifolds and assemblies described herein.

5 Each spray assembly 134, 140, 142 or other spray device may include an arrangement of discharge ports or orifices for directing wash fluid received from pump 152 onto dishes or other articles located in wash chamber 106. The arrangement of the discharge ports, also referred to as jets, apertures, or 10 orifices, may provide a rotational force by virtue of wash fluid flowing through the discharge ports. Alternatively, spray assemblies 134, 140, 142 may be motor-driven, or may operate using any other suitable drive mechanism. Spray manifolds and assemblies may also be stationary. 15 Movement of the spray arm assemblies 134 and 140 and the spray from fixed manifolds like spray assembly 142 provides coverage of dishes, silverware, and other dishwasher contents and articles 94 to be cleaned with a washing spray. Other configurations of spray assemblies may be used as 20 well. For example, dishwasher appliance 100 may have additional spray assemblies for cleaning silverware, for scouring casserole dishes, for spraying pots and pans, for cleaning bottles, etc. One skilled in the art will appreciate that the embodiments discussed herein are used for the 25 purpose of explanation only and are not limitations of the present subject matter.

In operation, pump 152 draws wash fluid in from sump 138 and pumps it to a diverter assembly 156, e.g., which is positioned within sump 138 of dishwasher appliance. 30 Diverter assembly 156 may include a diverter disk (not shown) disposed within a diverter chamber (not shown) for selectively distributing the wash fluid to the spray assemblies 134, 140, 142 and/or other spray manifolds or devices. For example, the diverter disk may have a plurality of 35 apertures that are configured to align with one or more outlet ports (not shown) at the top of diverter chamber (not shown). In this manner, the diverter disk may be selectively rotated to provide wash fluid to the desired spray device.

According to an example embodiment, diverter assembly 40 156 is configured for selectively distributing the flow of wash fluid from pump 152 to various fluid supply conduits, only some of which (e.g., 154) are illustrated in FIG. 2 for clarity. More specifically, diverter assembly 156 may include four outlet ports (not shown) for supplying wash 45 fluid to a first conduit for rotating lower spray arm assembly 134 in the clockwise direction, a second conduit for rotating lower spray arm assembly 134 in the counterclockwise direction, a third conduit for spraying rack assembly 126 (shown in FIG. 2) as a silverware rack, and a fourth conduit 50 for supplying only mid-level and/or upper spray assemblies 140, 142. Other configurations of diverter assembly 156 and/or other components (e.g., valves) may be used to allow various choices in the operation of the spray assemblies 134, 140, and 142 during a cleaning cycle.

55 The dishwasher appliance 100 is further equipped with a controller 160 (FIG. 2) to regulate operation of the dishwasher appliance 100. Controller 160 may include one or more memory devices and one or more microprocessors, such as general or special purpose microprocessors operable 60 to execute programming instructions or micro-control code associated with a cleaning cycle. The memory may represent random access memory such as DRAM or read only memory such as ROM or FLASH. In one embodiment, the processor executes programming instructions stored in memory. The memory may be a separate component from the processor or may be included onboard within the processor. Alternatively, controller 160 may be constructed 65

without using a microprocessor, e.g., using a combination of discrete analog and/or digital logic circuitry (such as switches, amplifiers, integrators, comparators, flip-flops, AND gates, and the like) to perform control functionality instead of relying upon software.

The controller 160 may be positioned in a variety of locations throughout dishwasher appliance 100. In the illustrated embodiment, the controller 160 may be located within a control panel area 162 of door 116. In such an embodiment, input/output ("I/O") signals may be routed between the control system and various operational components of dishwasher appliance 100 along wiring harnesses that may be routed through the bottom of door 116. Typically, the controller 160 includes a user interface panel/controls 164 (FIG. 1) through which a user may select various operational features and modes and monitor progress of the dishwasher appliance 100. In one embodiment, the user interface 164 may represent a general purpose I/O ("GPIO") device or functional block. In one embodiment, the user interface 164 may include input components, such as one or more of a variety of electrical, mechanical, or electro-mechanical input devices including rotary dials, push buttons, and touch pads. The user interface 164 may include a display component, such as a digital or analog display device designed to provide operational feedback to a user. The user interface 164 may be in communication with the controller 160 via one or more signal lines or shared communication busses.

It should be appreciated that the invention is not limited to any particular style, model, or configuration of dishwasher appliance 100. The example embodiment depicted in FIGS. 1 and 2 is for illustrative purposes only. For example, different locations may be provided for user interface 164, different configurations, including providing one or more rack assemblies 122, 124, 126 and one or more spray assemblies 134, 140, 142, to dishwasher appliance 100 may be used, different configurations may be provided for rack assemblies 122, 124, 126, different spray assemblies 134, 140, 142 and spray manifold configurations may be used, and other differences may be applied while remaining within the scope of the present subject matter.

Shown in FIG. 3, the perimeter of third rack assembly 126 may be defined by a wire framework 300. Wire framework 300 may include a floor 308 formed in combination with the floor portion of wire insert 302. Wire insert 302 may include at least two (2) of a hook 306, or the like, for removably coupling wire insert 302 to wire framework 300. The present example embodiment includes four (4) hooks 306. Wire insert 302 may be defined in the transverse direction T, between a first boundary wall 310 and a second boundary wall 312, whereupon hooks 306 may be positioned. In FIG. 3, wire insert 302 is shown coupled to wire framework 300 via hooks 306.

Shown in FIG. 4, a lower floor portion 316 of wire insert 302 may generally be configured to move beneath a third spray assembly 320. For example, wire insert 302 may be configured to translate within wire framework 300 and position lower floor portion 316 beneath, in the vertical direction V, third spray assembly 320. Wire insert 302 may include an upper floor portion 314 and the lower floor portion 316. The upper floor portion 314 and the lower floor portion 316 may be positioned at different heights with respect to the vertical direction V such that different size articles for washing may be placed upon wire insert 302. Lower floor portion 316 may be configured to interface, e.g., minimal gap, with floor 308 when wire insert 302 is inserted in wire framework 300. Thus, e.g., floor 308 may be nested against wire insert 302 when wire insert 302 is inserted in

wire framework 300. Moreover, lower floor portion 316 may be positioned generally coplanar with floor 308 such that lower floor portion 316 and floor 308 may collectively form a portion of the floor of third rack assembly 126.

Shown in FIGS. 5-8, third spray assembly 320 may be configured to removably couple, e.g., mount, to third rack assembly 126. For example, as may be seen in FIG. 5, a bottom portion 500 of third spray assembly 320 may include a protrusion 502 generally configured for attaching third spray assembly 320 to wiring 510 of third rack assembly 126. In general, third spray assembly 320 may attach to third rack assembly 126 via engaging protrusion 502 over wiring 510. Particularly, protrusion 502 may be a snap, or similar snap-like feature configured to removably attach third spray assembly 320 to third rack assembly 126. As may be seen in FIG. 6, third spray assembly 320 may include a channel portion 600 generally configured to guide one end of third spray assembly 320 while attaching third spray assembly 320 to third rack assembly 126. Particularly, channel portion 600 may include a c-shaped channel, or slot-like feature generally configured to engage with wire framework 300 of third rack assembly 126. Additionally or alternatively, channel portion 600 may be one of a plurality of channel portions 600 on the third spray assembly 320, e.g., as seen in FIG. 6, third spray assembly includes two (2) channel portions 600.

In general, third spray assembly 320 may rotate downward, in the vertical direction V, onto third rack assembly 126 such that protrusion 502 snaps onto wires 510 of third rack assembly 126. As may be seen in FIG. 7, third spray assembly 320 is shown in a mounting position 700. For example, channel portion 600 and protrusion 502 are positioned on opposing ends of the third spray assembly, such that channel portion may engage with wire framework 300 and third spray assembly 320 may rotate downward onto third rack assembly 126 in order for the protrusion 502 to snap onto wiring 510 of third rack assembly 126. As such, both channel portion 600 and protrusion 502 of third spray assembly 320 work to restrict movement of third spray assembly 320 when mounted to third rack assembly 126.

As may be seen in FIG. 8, a support wire 800 may extend under third spray assembly 320. Particularly, support wire 800 may extend along a central axis C of third spray assembly 320. Support wire 800 may generally provide additional structure to support third spray assembly 320 from drooping downward over the life of the spray assembly. In particular, third spray assembly 320 may self-support dish loads throughout the life of the spray assembly and the dish load along with hot water may tend to induce creep in third spray assembly 320 over time. As such, support wire 800 may aid to prevent sag/droop of third spray assembly 320.

As may be seen from the above, a dishwasher appliance may include a third rack assembly with a third spray assembly configured to removably attach to the third rack assembly. The third spray assembly may include a protrusion configured to snap onto wiring of the third rack assembly. The third spray assembly may further include a channel portion configured to guide third spray assembly into a mounting position, whereupon third spray assembly may rotate downward onto wiring of the third rack assembly.

This written description uses examples to disclose the invention, including the best mode, and also to enable any person skilled in the art to practice the invention, including making and using any devices or systems and performing any incorporated methods. The patentable scope of the invention is defined by the claims, and may include other examples that occur to those skilled in the art. Such other

examples are intended to be within the scope of the claims if they include structural elements that do not differ from the literal language of the claims, or if they include equivalent structural elements with insubstantial differences from the literal languages of the claims.

What is claimed is:

1. A dishwasher appliance defining a vertical direction, a lateral direction, and a transverse direction, the vertical, lateral, and transverse directions being mutually perpendicular, the dishwasher appliance comprising:
  - a tub defining a wash chamber;
  - a wash conduit in the wash chamber;
  - a first rack assembly slidably positioned within the wash chamber;
  - a first spray assembly positioned in the wash chamber and configured to direct wash fluids at the first rack assembly;
  - a second rack assembly slidably positioned in the wash chamber above the first rack assembly;
  - a second spray assembly positioned in the wash chamber and configured to direct wash fluids at the second rack assembly;
  - a third rack assembly slidably positioned in the wash chamber above the second rack assembly, the third rack assembly comprising a wire framework and a wire insert selectively mountable on the wire framework; and
  - a third spray assembly positioned within the third rack assembly and configured to direct wash fluid at articles located in the third rack assembly, the third spray assembly comprising,
  - a protrusion positioned at a bottom portion of the third spray assembly, the protrusion attachable to the third rack assembly in order to mount the third spray assembly to the third rack assembly, wherein the wire insert is slidably positionable within the wire framework beneath the third spray assembly, when the third spray assembly is mounted to the third rack assembly.
2. The dishwasher appliance of claim 1, wherein the protrusion is configured to snap onto wires of the third rack assembly.
3. The dishwasher appliance of claim 1, wherein a channel portion on the third spray assembly is configured to engage the third rack assembly in order to guide one end of the third spray assembly into mounting position.
4. The dishwasher appliance of claim 3, wherein the channel portion comprises a c-shaped channel.
5. The dishwasher appliance of claim 3, wherein the channel portion is one of a plurality of channel portions on the third spray assembly.
6. The dishwasher appliance of claim 1, wherein a support wire extends under the third spray assembly.
7. The dishwashing appliance of claim 6, wherein the support wire extends along a central axis of the third spray assembly.
8. The dishwasher appliance of claim 3, wherein the channel portion of the third spray assembly and the protrusion are positioned on opposite ends of the third spray assembly.
9. The dishwasher appliance of claim 1, wherein the third spray assembly is rotatable downwardly onto the third rack assembly to snap the protrusion onto wires of the third rack assembly.
10. The dishwasher appliance of claim 3, wherein both the channel portion and the protrusion of the third spray assembly

bly restrict movement of the third spray assembly when mounted to the third rack assembly.

11. A dishwasher appliance defining a vertical direction, a lateral direction, and a transverse direction, the vertical, lateral, and transverse directions being mutually perpendicular, the dishwasher appliance comprising:
  - a tub defining a wash chamber;
  - a wash conduit in the wash chamber;
  - a first rack assembly slidably positioned within the wash chamber;
  - a first spray assembly positioned in the wash chamber and configured to direct wash fluids at the first rack assembly;
  - a second rack assembly slidably positioned in the wash chamber above the first rack assembly;
  - a second spray assembly positioned in the wash chamber and configured to direct wash fluids at the second rack assembly;
  - a third rack assembly slidably positioned in the wash chamber above the second rack assembly, the third rack assembly comprising a wire framework and a wire insert selectively mountable on the wire framework; and
  - a third spray assembly positioned within the third rack assembly and configured to direct wash fluid at articles located in the third rack assembly, the third spray assembly comprising,
  - a protrusion positioned at a bottom portion of the third spray assembly, the protrusion attachable to the third rack assembly in order to mount the third spray assembly to the third rack assembly, and
  - a channel portion is configured to engage the third rack assembly in order to guide one end of the third spray assembly into a mounting position,
  - wherein the wire insert is slidably positionable within the wire framework beneath the third spray assembly, when the third spray assembly is mounted to the third rack assembly.
12. The dishwasher appliance of claim 11, wherein the protrusion is configured to snap onto wires of the third rack assembly.
13. The dishwasher appliance of claim 11, wherein the channel portion comprises a c-shaped channel.
14. The dishwasher appliance of claim 11, wherein the channel portion is one of a plurality of channel portions on the third spray assembly.
15. The dishwasher appliance of claim 11, wherein a support wire extends under the third spray assembly.
16. The dishwashing appliance of claim 15, wherein the support wire extends along a central axis of the third spray assembly.
17. The dishwasher appliance of claim 11, wherein the channel portion of the third spray assembly and the protrusion are positioned on opposite ends of the third spray assembly.
18. The dishwasher appliance of claim 11, wherein the third spray assembly is rotatable downwardly onto the third rack assembly to snap the protrusion onto wires of the third rack assembly.
19. The dishwasher appliance of claim 11, wherein both the channel portion and the protrusion of the third spray assembly restrict movement of the third spray assembly when mounted to the third rack assembly.
